US00D448049B1

(12) United States Design Patent (10) Patent No.: US D448,049 S
 Podgorney et al. (45) Date of Patent:  Sep. 18, 2001

(54) BEVERAGE VENDING MACHINE

- (75) Inventors: Gerald J. Podgorney, St. Louis; Roger H. Decker, St. Peters, both of MO (US); Kurt Botsai, Thousand Oaks, CA (US); Cary Chow, Venice, CA (US); Juan Cilia, Thousand Oaks, CA (US); Chris Glupker, Van Nuys, CA (US); Ravi Sawhney, Calabasas, CA (US); Frank Zinni, Capistrano Beach, CA (US); Hirotomi Teranishi, Calabasas, CA (US)
- (73) Assignee: Crane Co., Stamford, CT (US)
- () Term: 14 Years
- (21) Appl. No.: 29/107,964
- (22) Filed: Jul. 16, 1999
- (51) LOC (7) Cl. 20-01
- (52) U.S. Cl. D20/5; D7/306; D7/312
- (58) Field of Search D7/305-312; D20/1, D20/4, 5; 99/282, 283, 285, 330, 357, 403, 407-410, 415; 222/129.1

(57) CLAIM

The ornamental design for a beverage vending machine, as shown and described.

DESCRIPTION

FIG. 1 is a perspective view of a beverage vending machine showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken line showing on FIGS. 1, 2, 4 and 6 is for illustrative purposes only and forms no part of the claimed design.
